To all whom it may concern:

Be it known that I, MARCEL M. MIRABEAU, a subject of the Emperor of Germany, residing in the city of New York, borough of Manhattan, in the county and State of New York, have invented and produced a new and original Design for a Watch-Chain and Necklace, of which the following is a full, clear, and exact description.

10 The invention relates to jewelry, such as guard or watch chains and necklaces.

Reference is to be had to the accompanying drawing, forming a part of this specification, in which the figure is a plan view of a watch-chain and necklace, showing my design.

15 The design in its entirety consists of an endless chain A, appearing ornamented at its lower end with a hook B and on its runs or sides with buttons C, located opposite each other and connected by a necklace part D, shown as consisting of a number of parallel chains D', having an ornamental button D' at the middle.

The leading feature of my design consists of the chain A and the necklace part extending from one side of the chain to the other.

I claim—
